John H. Fitzpatrick Inventor
Attorney H. Anderson

UNITED STATES PATENT OFFICE.

JOHN H. FITZPATRICK, OF PEEKSKILL, NEW YORK.

GAME OF NINE.

1,405,195.

Specification of Letters Patent. Patented Jan. 31, 1922.

Application filed February 15, 1921. Serial No. 445,147.

To all whom it may concern:

Be it known that I, JOHN H. FITZPATRICK, a citizen of the United States, and resident of Peekskill, in the county of Westchester 5 and State of New York, have invented certain new and useful Improvements in the Game of Nine, of which the following is a specification.

This invention relates to pastime games, 10 and has for its object a fireside game simulating base ball. The object is attained by the means set forth in this specification and the accompanying drawings, in both of which like letters and figures refer to similar 15 parts throughout the several views.

Fig. 1 is a plan of the game board. Fig. 2 is a longitudinal section through line B of Fig. 1. Figs. 3 and 4 are details relating to the spring actuated ball bat.

20 The game board consists of a rectangular base A upon which is secured a flanged form of the figure 9, the flange comprising the limb d, the loop a b, and the limb and loop connecting part c. The loop is not joined to 25 the part c, an opening at l being left for the free passage of the balls, in playing the game, to the field e.

20 Rows of balls t t' are shown at the sides of the board, the two sets of nine balls each 30 having different colors, the row t may be red, the row t' may be blue, the colors not being material.

The game is played by placing a ball at the beginning of the limb d, as at 8. A ball 35 club 1 is attached to a spring, so that when drawn back from the position shown, then released, the club will strike the ball and drive it against the flange into the field e. The ball may be struck hard enough to cause 40 it to enter and traverse the path around the circle a b several times, or a blow may be so light as to cause the ball to just enter the field. If the field were level there would be little choice as to results between a light or 45 a heavy blow, as the ball would have a tendency to stop without leaving the flange. To prevent such negative results the field is made concave, as by the line f, Fig. 1, and as shown at C in Fig. 2, and the concavity is 50 elongated as at i, Fig. 1. The edge f of the concaved field is a distance from the flange a little less than half the diameter of the ball, as at 9, Figs. 1 and 2, so that if the tendency of a ball were to stop at or against the 55 flange, gravity will cause it to leave the

flange and it is liable to be caught in one of the depressions r, of which there may be ten, more or less, in the field e.

The hole n is the most difficult one in which to land or lodge a ball, and it is considered the "home" base. If the ball is given considerable velocity it will keep to the flange for several circuits around the loop, even passing over the elongated depression i, but through the part i is the surest way to 60 the home base, so that the player will aim to have the balls enter the depressed field from that direction. The other holes r have values according to the rules of the game; a home run counting from one number to another, 65 as from one to two, two to three, and so on, while the other holes count as points toward a "home." 70

When a ball is placed as at 8 and is given a smart blow it has a tendency to jump over 75 the flange. To prevent that a curved way h is provided on the flange, to hold the ball to its path until it is fairly rolling on its way.

To regulate the blow to be given to the balls, the club 1 is attached to a spring 2, 80 Figs. 3 and 4, one end of the spring being fast in a collar 5, as at 7, Fig. 3. The collar 5 is placed over a screw-stud 4, Fig. 4, resting on a washer 6. The thumb-nut 3 on the screw binds the collar 5, so that by shifting 85 the position of the club, and securing it by means of the thumb-nut, the force of the club is regulatable and can be varied at the will of the player.

On two corners of the board are game 90 counters m m, comprising revolvable pointers and indexes. The balls when idle are held in recesses in the board, as indicated at u, Fig. 2.

Having described my invention, what I 95 claim and desire to secure by Letters Patent, is—

1. The combination in a game board comprising a base, a raised flange upon the base in the form of a figure 9, the end of the loop 100 of the 9 separated from the rim of the 9, the enclosure within the loop of the 9 having an elongated depression the depression elongated and deepened in the direction of the limb of the 9, the depression beginning at a 105 distance along the flange a little distance less than half the diameter of the balls used, a horizontally projecting flange on the end of the limb of the 9, recesses in the depression, a club for striking the ball, a stud in 110

the base, a collar on the stud connected with the said club, a retractile spring acting upon the collar, and a thumb-nut on the stud.

2. The combination in a game board of a base, a raised flange upon the base in the form of a figure 9, the end of the loop of the 9 separated from the limb of the 9, the enclosure within the loop of the 9 having an elongated unequally curved depression the

depression elongated and deepened in the 10 direction of the limb of the 9, the depression beginning at a distance along the flange of a little less than half the diameter of the playing balls, recesses in the depressed field, an adjustable striking club and means uniting the club and the base for adjusting the 15 club, and balls to go with the board.

JOHN H. FITZPATRICK.
